(57) **CLAIM**

The ornamental design for a main body for mobile phone, as shown and described.

DESCRIPTION

FIG. 1 is a rear perspective view of the main body for mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is another rear perspective view thereof, shown with environment.

The broken lines that are immediately adjacent to the claim, and define unshaded regions, represent the bounds of the claim, while all other broken lines are directed to environment; the broken lines form no part of the claimed design. In FIG. 2, the unshaded surface that directly adjoins the claimed solid line edge forms no part of the claimed design.
